UNITED STATES PATENT OFFICE.

LEO A. CHMARA AND ANASTASIU A. CHMARA, OF BAY CITY, MICHIGAN.

BROOM-BRACE.

1,164,924.

Specification of Letters Patent. Patented Dec. 21, 1915.

Application filed September 23, 1913. Serial No. 791,424.

To all whom it may concern:

Be it known that we, LEO A. CHMARA and ANASTASIU A. CHMARA, citizens of the United States, residing at Bay City, in the county of Bay and State of Michigan, have invented certain new and useful Improvements in Broom-Braces, of which the following is a specification.

The object of this invention is to provide a broom brace which will act to stiffen the straws after the same have become weakened by use so that the straws will not flex so greatly under sweeping pressure.

It is not the object of this invention to provide a rigid broom brace which will unyieldingly stiffen the broom straws, but on the other hand, it is the object of this invention to yieldingly stiffen the broom straws so they will flex to a certain extent under sweeping pressure but will not be so limber as to cause the ends of the broom straws to lie flat upon the surface to be swept.

It is well known that brooms are usually discarded long before the straws are entirely worn out owing to the fact that the straws become excessively limber and limp and it becomes difficult to manipulate the broom in such a way as to properly sweep a surface. This is especially true where brooms are used for scrubbing purposes. Sometimes new brooms are objectionably flexible especially where the straws are of greater than the normal length.

It is the object of our invention to provide a cheap and efficient attachment which can be readily applied to any kind of broom to brace the straws thereof sufficiently so that the same will not be over flexible under sweeping pressure.

Our invention will be more fully described in connection with the accompanying drawing and will be more particularly pointed out in and by the appended claim.

In the drawing:—Figure 1 is a view in elevation illustrative of one form of our invention attached to a broom. Fig. 2 is a similar view of a slightly modified form of the invention, and showing the same detached from a broom. Fig. 3 is a sectional view on line 3—3 of Fig. 2.

Like characters of reference designate similar parts throughout the different figures of the drawing.

Referring more particularly to Fig. 1, the lower end of a broom handle is indicated at 1, and the broom head at 2. The broom body

2 is composed of longitudinally disposed straws having sweeping ends 4. Suitable binding 5 is disposed near the upper portion of the broom body. In this form, the device of our invention includes a pair of U-shaped band portions 6 and 7 adapted to be connected at their ends to form a band for embracing the broom body above the sweeping end 4 thereof. In the form illustrated, the band portion 7 is provided with a plurality of notches 8 and the band portion 6 is provided with a stud 9, for engagement with said notches to provide for expansion or contraction of the broom band. It will be understood that while only one side is shown the other side will be of identical construction with the side shown.

We may provide additional adjusting means which may consist of a slot 10, formed in the band portion 7, and a stud 11 carried by the band portion 6 and projecting through said slot 10. A thumb nut 12 may be provided to lock the parts. This additional adjusting means may serve as an effective lock to prevent the stud 9 from springing out of engagement with the notches 8.

We provide means for flexibly connecting the band to the base portion of the handle 1, and as shown, such means may consist of a rod 13 having its ends secured to the band portions 6 and 7, as indicated at 14, and extending upwardly from the band about the lateral edges of the broom body in a manner to conform to the shape of the latter. The rod 13 extends abreast of the head 2 and above the same where it is bent to form eyes 15 through which a bolt 16, having a thumb nut 17, extends. As will be clearly seen by reference to Fig. 1, the bolt 16 is disposed laterally at one side of the broom handle 1. The rod 13 is bent to form a loop 18 extending from the eyes 15 about the handle 1 so that the loop and the bolt 16 will firmly secure the rod 13 to the handle.

The rod 13 is preferably resilient so that when the broom is subjected to downward sweeping pressure it will permit of flexure of the broom straws to a limited extent so as to provide for the proper sweeping action. Should the broom straws become too flexible, the device of our invention will stiffen the same sufficiently so that proper sweeping action can be obtained. The means for adjusting the broom band to contract or expand the same is especially serviceable where

it is desired to stiffen the broom straws to a greater extent where the broom is used for scrubbing, in which event contraction of the band would render the broom straws 5 exceedingly stiff so that a firm scrubbing contact may be had with the floor surface.

In the form shown in Fig. 2, the band portions 19 and 20 are provided with slots 21 and 22, respectively, through which a 10 screw 23 extends, as shown in Fig. 3. The screw is provided with a head 24, and with a thumb nut 25 whereby the band can be effectively locked when adjusted to the desired extent of contraction or expansion.

15 A rod 13, in all respects similar to that of the preferred construction as shown in Fig. 1, extends upwardly from the band portions 19 and 20 but between the eyes 15 we interpose an expansion spring 26 so as to 20 normally separate the eyes. The bolt 16 extends through the eyes 15 and the spring and is provided with a thumb nut at one end.

It is believed that the advantages and 25 utility of our invention will be clearly understood from the foregoing, and while we have herein shown and described one specific form of the invention we do not wish to be limited thereto except for such limitations as the claim may import.

We claim:

A broom attachment comprising a pair of substantially U-shaped strap metal members, said members being received around

the straws of the broom head adjacent the 35 sweeping ends thereof the ends of one of said members overlying the ends of the other of said members, one of said members provided with a plurality of notches adjacent its free extremities, said notches communicating with the upper edge thereof, studs carried by the other of said members adjacent its free extremities for engagement with certain of said notches, one of said members provided with slots, adjacent 40 its free extremities, screw threaded studs on the other of said members passing through said slots to prevent vertical movement of the adjacent ends of said members and the consequent displacement of said first 45 mentioned studs from said notches, fastening members on said second mentioned studs, a flexible rod having its ends secured to said members, the adjacent portions of said rod projecting upwardly and bent to conform with the contour of the broom head, the intermediate portion of said rod being bent to form a pair of eye loops and embrace 50 the handle, and means connecting said eye loops and the handle.

In testimony whereof we affix our signatures in presence of two witnesses.

LEO A. CHMARA.

ANASTASIUS A. CHMARA.
